HIGH-FREQUENCY FURNACE

Klaas Posthumus, Eindhoven, Netherlands, assignor to Hartford National Bank and Trust Company, Hartford, Conn., as trustee

Application October 28, 1946, Serial No. 706,237
In the Netherlands July 24, 1945

Section 1, Public Law 690, August 8, 1946
Patent expires July 24, 1965

3 Claims. (Cl. 219—47)

1

This invention relates to a high-frequency furnace which consists of a tube oscillator, where the article to be heated is placed within the generator coil, more particularly to a high-frequency furnace for hardening purposes.

When, in a high-frequency furnace referred to, the article to be heated is taken out of the generator coil, the high-frequency voltage increases very strongly owing to the fact that the quality of the generator circuit has increased. The grid current also increases strongly in such manner that, in order to avoid burning of the grid leakage-resistance, the voltage or a circuit characteristic has to be readjusted. If no leakage-resistance, but a fixed negative grid voltage is used, the anode current increases and the tube is jeopardized. In the case of using a leakage-resistance, the negative voltage rises and consequently the anode current does not become so strong. If the articles to be heated have to stay for a comparatively long time in the coil this readjustment does not constitute a series drawback in general. Of course, control members must be available. With furnaces for hardening purposes, however, the article to be treated is kept in the coil for a very short time, usually for a few seconds only. In this case, it is consequently very objectionable to control the voltage or, as the case may be, to cut it in and out or to control either any of the circuit elements or the coupling, because this control then takes more time than the thermal treatment itself, thus working very ineffectively.

By the present invention this drawback is met by interposing a diode in the grid circuit of an oscillator tube of a high-frequency furnace, the cathode of which is connected to the grid and the saturation current of which is equal to the maximum permissible grid current.

If there is an article in the coil, the diode transmits the grid current without undue voltage losses. When the article is withdrawn from the coil the grid current cannot surpass the maximum value despite an increase in high-frequency voltage. The grid receives a strongly negative voltage, so that the anode current and consequently also the high-frequency voltage of the circuit do not exceed undue values. The advantage over all other controls consists in that this method is entirely devoid of inertia and in that no additional control members need be available, it being only necessary that the diode in the grid circuit should be capable of withstanding a proper voltage.

True, it is already known with transmitters

2

to insert a diode in the grid circuit of an oscillator tube to prevent the grid current from reversing its sign or from acquiring an unduly high value, but in these arrangements the diode is only started up by disturbances which would cause a reversal or abnormal increase of the grid current and not, as with the aforesaid high-frequency furnace, by changing the load at any one time.

10 In order that the invention may be clearly understood and readily carried into effect, it will now be described more fully with reference to the accompanying drawing, given by way of example, which represents a high-frequency oscillator for a high-frequency furnace according to the invention.

In the drawing the oscillator tube of a high-frequency furnace is denoted by 1, the cathode by 2, the grid by 3 and the anode by 4.

20 The generator circuit consists of a condenser 5 and a coil 6. The grid is connected to the generator circuit through a diode 7, which is bridged by a condenser 8. The grid is connected to the cathode of the diode. The cathode of the triode is fed from the low tension mains through the intermediary of a transformer 10, whereas the anode is supplied with low-frequency alternating current through the terminals 9. Within the generator coil 6 is placed a steel shaft 11 which 30 has to be hardened, to which end it must be kept in the coil for two seconds. When the shaft 11 is inside the coil 6, the quality of the circuit is poor and the high-frequency voltage keeps within the permissible limits. If, however, the shaft is withdrawn, the quality of the circuit increases. The high-frequency voltage increases and consequently also the grid current, but only to the saturation current of the diode 7. The negative grid voltage increases, so that the anode 40 current and consequently the high-frequency voltage can no longer increase.

What I claim is:

1. A high-frequency oscillator comprising an electron discharge tube having a cathode, a grid and an anode, a resonant circuit coupled between said anode and said grid, and a diode discharge device having a cathode and an anode, said device being interposed between said grid and said circuit with the cathode of said device connected to said grid and the anode thereof connected to one end of said circuit, said device being characterized by a value of saturation current which corresponds to the maximum permissible grid current of said tube.
- 55 2. A high-frequency oscillator comprising an

electron discharge tube having a cathode, a grid and an anode, a resonant circuit constituted by a coil in parallel with a condenser, one end of said circuit being connected to the anode of said tube, a coupling capacitor, the other end of said circuit being connected through said capacitor to the grid of said tube, and a diode discharge device having a cathode and an anode, said device being connected in parallel with capacitor with the cathode of said device being connected to the grid of said tube and the anode of said device being connected to said other end of said circuit, said device being characterized by a value of saturation current which corresponds to the maximum permissible grid current of said tube.

3. A high-frequency oscillator for induction heating comprising an electron discharge tube having a cathode, a grid and an anode, a resonant circuit constituted by an induction heating coil in parallel with a condenser, one end of said circuit being connected to the anode of said tube, a diode discharge device having a cathode and an anode, the cathode of said device being connected to the grid of said tube, the anode of said device being connected to the other end of said circuit, a coupling capacitor shunted across said device, and means to apply a low-frequency en-

ergizing potential between the cathode of said tube and a tap on said coil, said device being characterized by a value of saturation current which corresponds to the maximum permissible grid current of said tube.
